UNITED STATES PATENT OFFICE.

HENRY H. COLLINS, JR., OF PHILADELPHIA, PENNSYLVANIA, ASSIGNOR
TO A. M. COLLINS MANUFACTURING COMPANY, OF PHILADELPHIA, PENNSYLVANIA, A CORPORATION OF PENNSYLVANIA.

DESIGN FOR A CARD-MOUNT.

SPECIFICATION forming part of Design No. 37,087, dated August 16, 1904.

Application filed April 18, 1904. Serial No. 203,810. Term of patent 7 years.

To all whom it may concern:

Be it known that I, HENRY H. COLLINS, Jr., a citizen of the United States, residing in Philadelphia, Pennsylvania, have invented a certain new, original, and ornamental Design for a Card-Mount, of which the following is a specification.

My design is shown in the accompanying drawings, in which—10 Figure 1 represents a face view of the card-

mount, and Fig. 2 an enlarged transverse section of part of the same.

I claim and desire to secure by Letters Patent—

The ornamental design for a card-mount as 15 shown.
